SEALED CONTAINER

James D. Reifsnyder, New York, N. Y., assignor to
 Lily Tulip Cup Corporation, New York, N. Y.,
 a corporation of Delaware

Application September 17, 1935, Serial No. 40,891

1 Claim. (Cl. 229—5.6)

This invention relates to sealed containers, and more particularly to containers having removable closure means which are sealed in position on the containers by a fusible sealing material.

An object of this invention is to produce a container of the indicated type having its closure so sealed in place by a fusible sealing material that air pressure or vacuum will be held within the container during the shipping, handling and merchandizing of such container. Other objects of the invention and of details associated therewith will appear from the following specification.

The invention is particularly adapted to containers made of paper or other fibrous material which are used as a means for packing and shipping commodities which are to be sold in this form to the consumer. Containers of this type are usually frusto-conically shaped, the base portions thereof being of smaller diameter than the mouth or top portions and their size usually depends upon the weight of the commodity that is to be packed therein. The containers may be treated with paraffin or other suitable material capable of sealing the pores of the fibrous material of which the containers are constituted and rendering them impervious to fluids. Usually these containers are closed by a disc cover which is supported on a shoulder provided on the container bodies or is snugly fitted into an internal groove provided adjacent to the upper edges of the containers. As it is necessary with certain kinds of commodities to maintain them under pressure or in a vacuum until they reach the consumer, it is desirable that the covers of the containers in which such commodities are packed be sealed in position so no fluid can escape from or enter into the containers until they are opened by the consumer. I am aware that it has been attempted to hermetically seal such containers by smearing paraffin or other materials around the peripheral edges of the covers where they join with the containers but I have found that such seals are unsatisfactory where the contents of the containers are packed under pressure or in a vacuum and are not strong enough to successfully withstand the handling that such containers undergo during the shipping and merchandizing of the same.

A perfectly sealed container is obtained in accordance with the present invention, by first providing the upper edge portion of the empty container with a coating of paraffin or other suitable material which extends down to the lowest point where the cover thereof is in contact with the container. After the container has been filled

with the desired commodity and the cover inserted in place, melted sealing material such as paraffin is then applied to the upper edge portions of the container and to the peripheral edge of the cover where it joins with the container. I have found that by proper control of the temperature of the paraffin which is thus applied that the paraffin which was first coated on the container fuses sufficiently without flowing to enable the two masses of paraffin to combine together and form a homogeneous mass. When the mass hardens the cover is in effect solidified with the container and a seal is provided which will enable the containers to hold air pressure or vacuum over an extended period without leakage and which will stand up under the rough usage such containers receive during shipping, handling and merchandizing without becoming inoperative.

The nature and utility of the invention will be better understood from the following description taken in conjunction with the drawing in which the invention is shown embodied in a paper container of the aforementioned type for the purposes of illustration and in which Fig. 1 is a side elevation, partly in section, of a portion of a sealing device illustrating the manner in which the sealing material is applied to the container; Fig. 2 is a perspective view, partly in section, of a filled container after the cover has been sealed in place; Fig. 3 is an enlarged detailed sectional view of a portion of a container before the cover has been sealed in position and Fig. 4 is a similar view of a container after the cover has been sealed in position.

Referring more particularly to the drawing, the reference character 10 designates a frusto-conically shaped container made from fairly heavy paper stock in a manner well known in the art and having a bottom spaced up from the bottom edge of the container as is usual in containers of this type. The upper edge portion of the cup is slightly greater in diameter than the main body portion of the container so that a shoulder is formed therebetween, such shoulder furnishing a seat for accommodating a disc closure 13. The upper edge portion of the container above the shoulder is curved inwardly, such curling operation having been continued until a bead 12 is formed along the upper edge of the container, the outer edge portion of the cover disc 13 being fixedly received within the recess 11 formed between the bead 12 and the inner shoulder provided at the top part of the main body portion of the container. Prior to placing the cover disc 13 in position and securing it in place by the

bead 12, the formed container is provided with a coating of paraffin or other suitable material which may be applied by passing the container through a bath of the material. When the coating material is applied in this manner, I find that the best results are obtained by holding the container in tilted position with its open end downward and rotating the container in this position about its central axis during its passage through the bath. When the material is applied as aforesaid the coating on the container will be thin and even throughout. The extent to which the container is to be covered by the coating material is dependent upon the kind of commodity that is to be packed therein. If the commodity requires a completely sealed container, the entire inner and outer surfaces are covered, as shown in the drawing, by the inner and outer coatings 14 and 15 respectively. If, however, the commodity to be packed in the container does not require that the body portion of the container be sealed, the coating material may be applied only to the upper edge portion of the container or may be applied only to that portion of the inner surface of the container which will be in contact with the peripheral edge of the cover. In the latter case, the coating material may be applied with a brush instead of passing it through a bath of the material. This initial coating of the container is then allowed to harden.

The container is then ready to be filled with the commodity which is to be packed therein. The filling of the container is usually done in a filling apparatus which discharges into the container the proper amount of the commodity to be contained therein. When the container is filled, the cover 13 is then forced into place in the mouth portion thereof so that the outer peripheral edge of the cover seats on the shoulder provided between the upper edge portion of the container and the main body portion thereof. The cover 13 is usually made of heavier paper stock than the container proper and is preferably impregnated with paraffin or other suitable material so that it is impervious to fluids. As a result of such treatment, a thin covering or film of the sealing material is provided on the exterior surfaces of the cover. The upper edge portion of the container may then be curled or rolled in any suitable manner so as to form the bead 12 which locks the cover securely in position against the shoulder of the container and renders that portion of the container sufficiently rigid to withstand the strains or pressures to which it will be subjected during the handling, shipping and merchandizing of the container.

The filled container is then subjected to a sealing bath of paraffin or other suitable material to hermetically seal the contents of the container. In carrying out this step of my invention, as well as the initial coating step previously described, I may utilize a sealing apparatus such as is disclosed in my United States Letters Patent No. 2,119,720 issued June 7, 1938, and sufficient of which is shown in Fig. 1 of the drawing for the purpose of describing this operation. For utilizing this apparatus for applying the second coating of sealing material to the filled container, the bottom end portion of the container is inserted in an enlarged head portion at the outer projecting end of one of the container holders of the apparatus just prior to the passage of said holder over a tank 18 positioned close below the path over which the container travels and containing a suitable sealing material such as paraffin. The

enlarged head portion of the holder, designated generally by the reference character 17, is provided with a plurality of outwardly extending pivoted arms (not shown) which are adapted to engage with the inner surface of the bottom end portion of the container and support the container securely on the holder while it is being carried through the bath. The enlarged head portion 17 is provided with a stub shaft 19 which is rotatably supported at its inner end in a bearing 20. The bearing 20 is pivotally supported on a pair of arms 21 by a pin 22 which extends through a downwardly projecting portion on the underside of the bearing, thereby enabling a roller 23 on said bearing to follow the upper surface 1 of the track 24 as it changes from a horizontal position to an inclined position to dip the container in the bath. As shown in the drawing, the bevel of the track is such that only the upper end portion of the container and the outer peripheral edge portion of the cover disc are dipped into the container, such portions of the covered container being evenly covered by the sealing material as the container is rotated about its central axis during its passage through the bath.

The paraffin bath is maintained at a temperature that will fuse the coating material originally applied to the container sufficiently without flow to enable the paraffin now applied on such original coating to combine therewith into a homogeneous mass and also to enable the contacting layers of the original coating to combine together into a homogeneous mass. Thus it will be seen that the paraffin added as a result of this step will combine with the original coating on the outer surface of the upper end portion of the cup and the bead 12 to form a thick homogeneous layer of sealing material on the outer sides of such portions as indicated by the reference character 25 in Fig. 4 of the drawing and also to form an annular homogeneous mass of sealing material in the seam between the bead 12 and the outer edge portion of the cover disc 13 as is indicated by the numeral 26, such mass being homogeneous with the layer 25 and the film of sealing material on the outer surface of the cover disc. Those portions of the original layers of coating material which are in contact in the bead 12, between the bead 12 and the upper surface of the edge of the cover disc, between the side edge of the cover disc and the inner side of the upper edge portion of the container and between the under surface of the edge of the cover disc and the container shoulder will also be fused together by the heat of the bath into a homogeneous mass, as is indicated by the reference character 27, such seal terminating at the edge of the shoulder at 28. Thus when the sealing material has hardened, the cover is in effect solidified with the container and a seal is provided which will enable the container to hold air pressure or vacuum over an extended period and will satisfactorily withstand relatively rough usage. The thickness of the sealing material along the outer upper edge portion of the container will be approximately twice as thick as the original layer of sealing material while the thickness of the sealing material at 26 will be appreciably greater. The thickness of the sealing portions may, of course, be varied by varying the period that the container is subjected to the bath. The thickness of the seal, however, along the contacting surfaces of the container which are not reached by the sealing material of the second bath depends upon the amount of 75

coating material which has been applied in the original bath.

Having thus described my invention in detail with reference to its preferred form, it will be apparent to those skilled in the art that various changes and modifications may be made therein without departing from the spirit and scope of the invention and I intend in the appended claim to cover such changes and modifications as are within the scope of the invention.

I claim:

A seal for a paper receptacle which has been submitted to a treatment of paraffin prior to the insertion of a commodity therein, comprising a receptacle body having at its open end an end section offset outwardly to provide an interior annular shoulder, a flat closure disc seated on said shoulder, the portion of said end section disposed outwardly from said flat disc being curled inwardly upon itself so that the peripheral edge portion of the disc is subjected to clamping pressure directly effective between said shoulder and the curled-in part of said end section and in alignment with the side walls of said receptacle body, and paraffin fused together from a point adjacent the inner edge of said shoulder and between such shoulder and the edge portion of said disc, outwardly to the outer edge of said shoulder, around the edge of said disc and then, in one direction, between the edge portion of said disc and the under portion of the curled edge, and, in another direction, between a part of said end section and the curled-in edge thereof and those other parts of the interior surface of said end section which are curled against each other, and augmented by supplemental fused paraffin between the non-contacting parts of the curled-in portion of the end section and the outer surface of the peripheral edge portion of the disc and around the outer surface of the curled edge of the body to a point beneath the outer part of said shoulder, the said portions of fused paraffin being connected together and forming an integral mass which fills in and seals the spaces between the receptacle body and the disc in the regions specified.

JAMES D. REIFSNYDER.
